(57) **CLAIM**

The ornamental design for an inflatable packing material, as shown and described.

DESCRIPTION

FIG. 1 is a left front isometric view of one embodiment of an inflatable packing material showing my new design;

FIG. 2 is a top plan view thereof, the bottom being a mirror image of the top.

FIG. 3 is a left front isometric view of the embodiment of FIG. 1, showing the inflatable packing material in an inflated condition;

FIG. 4 is a top plan view thereof, the bottom being a mirror image of the top;

FIG. 5 is a front elevational view thereof;

FIG. 6 is a rear elevational view thereof; and,

FIG. 7 is a right side elevational view thereof, the left side being a mirror image of the right side.

The lines drawn with short evenly spaced dashes represent perforations and are part of the claimed design.

The broken lines drawn as alternating long and short dashes in the drawings depict portions of the inflatable packing material that are not part of the claim. The broken lines and the structures and features they depict form no part of the claimed design.
